WHEEL MOUNTING

Raymond A. Irwin, Manitowoc, Wis., assignor to Kaysun, Inc., Manitowoc, Wis., a corporation of Wisconsin

Application March 31, 1954, Serial No. 419,950

1 Claim. (Cl. 46—221)

This invention relates to wheels for toy and model vehicles, especially those molded of plastic material, and refers more particularly to means for rotatably mounting and retaining wheels on the axles of such vehicles.

There has long been a need for a satisfactory means for retaining a plastic wheel on its axle on such vehicles as toy and scale model automobiles, race cars, airplanes, carriages and the like. Such vehicles are frequently sold in kit form, an example being the kits for plastic scale models of "antique" automobiles which are enjoying widespread popularity.

Heretofore the builder of such a kit was usually required to perform some difficult or messy operation in order to secure the wheels onto the axles. For example, he may have been required to cement a retainer in place on the outer end of the axle to prevent the wheel from coming off, or to deform the end portion of the axle, as by heating the same, to accomplish this result. Either expedient was unsatisfactory, since the users of such kits are frequently children or other persons having only slight manual dexterity. As a result the appearance of the finished article was often spoiled, and if not, one or more wheels would be so securely held on the axles that they would not turn.

Obviously, the same problem was encountered in the manufacture of toy and model vehicles sold as assembled units, where the means heretofore used to secure the wheels onto the axles required a disproportionately large amount of time and effort.

Thus, for both kits and assembled toy and model vehicles, it is particularly important that the means provided for securing its wheels in place be extremely simple, require no special tools or materials, call for little or no mechanical skill or dexterity, and, in short, be virtually foolproof.

It is accordingly, an object of the present invention to provide a construction whereby a plastic wheel for a toy or model vehicle may be freely rotatably journaled on the vehicle axle in such a manner that axial displacement of the wheel off of the axle is precluded without the necessity for deforming the axle or installing a separate retaining member thereon.

Another object of this invention resides in the provision of a detent-like retainer for a plastic wheel of the character described which permits installation of the wheel on an axle by merely pressing the wheel onto the axle.

A further object of this invention resides in the provision of means for rotatably mounting a plastic wheel on a toy or miniature vehicle, which utilizes the resilience of the plastic material from which the wheel is fashioned to provide a detent-like connection between the wheel and axle, and which connection, because it does not depend upon a separate retaining element or deformation of the axle, endows the wheel hub with a very realistic appearance simulating the hub-cap of a full scale vehicle.

With the above and other objects in view, which will appear as the description proceeds, this invention resides

2

in the novel construction, combination and arrangement of parts substantially as hereinafter described and more particularly defined by the appended claim, it being understood that such changes in the precise embodiment of the hereindisclosed invention may be made as come within the scope of the claim.

The accompanying drawing illustrates one complete example of the physical embodiment of the invention constructed according to the best mode so far devised for the practical application of the principles thereof, and in which:

Figure 1 is a perspective view of a wheel in position to be assembled onto an axle, the wheel and axle being provided with the retaining means of this invention;

Figure 2 is a radial sectional view through the wheel and showing the same in an initial position of assembly with the axle;

Figure 3 is a view similar to Figure 2 but showing the connection between the wheel and the axle in the act of being completed; and

Figure 4 is a view similar to Figure 2 but showing the wheel properly mounted on the axle.

Referring now more particularly to the accompanying drawing, the numeral 5 designates generally a wheel of the type used on miniature automobiles, wagons and the like, and adapted to be freely rotatably mounted on an axle 6. Both the wheel and axle are preferably molded from a slightly resilient or elastic plastic material, such as impact styrene or acetate.

The wheel may of course have any of a wide variety of forms other than that shown, but in any event it has a hub portion 7 which in this instance is shown as projecting axially to one side of the wheel. A bore 8 of uniform diameter extends through the hub portion and accommodates the axle, which has a slightly smaller diameter than the bore of the hub so that when mounted the wheel has a free running fit on the axle.

At its axially outer end the hub has an integral inwardly turned annular lip or flange 10 which provides one element of the connection by which the wheel is held on the axle. The other element of this connection comprises an integral button-like axial extension 11 on the axle. The head 12 of this extension is round and has a diameter slightly smaller than or at least no longer than that of the axle so as to pass freely through the bore 8 in the hub, but larger than the bore of the lip or flange 10. Hence, for the head 12 to be passed through the bore or aperture defined by the flange or lip 10 requires the exertion of a fair amount of force. Once this is done the flange or lip encircles the neck portion 13 of the extension which is sufficiently smaller in diameter than the bore of the lip as not to interfere with free rotation of the wheel.

With the wheel installed as shown in Figure 4, outward axial displacement thereof is prevented by the outer face of the hub bearing against the abrupt shoulder 15 formed by the underside of the head 12.

It will thus be seen that the wheel may be installed on the axle by simply pressing the wheel onto the axle as shown in Figures 2, 3 and 4. Considerable axial pressure will of course be required to snap the flange or lip 10 over the head 12 of the button-like extension, but this part of the operation is facilitated by rounding the axially outer end of the head and tapering the bore of the flange, as at 14, so that the flange cams itself over the head. The inherent resilience of the plastic comprising the wall of the hub and the flange enables the bore of the flange to stretch slightly as the flange is carried or snapped over the head.

Inward axial displacement of the wheel from its correct position on the axle is preferably prevented by an outwardly facing shoulder 16 against which the inner end

of the hub abuts, and which in this instance simulates a brake drum. The wheel is thus axially confined between the head 12 and the shoulder 16 and since both of these surfaces and also the facing portions of the wheel are normal to the wheel axis the wheel is held in place in a manner not subject to binding as would be the case if the inclined inner end 14 of the flange were relied upon to define part of the means for holding the wheel in its proper position.

From the foregoing description, taken together with the accompanying drawing, it will be readily apparent that this invention provides an extremely simple and efficient manner of securing a wheel on the axle of a toy or model vehicle without interfering with its free rotation on the axle, and without necessitating deformation of the axle or the installation of a separate retaining member, so that the wheel hub has a neat and realistic appearance.

What I claim as my invention is:

Means for retaining a wheel molded of plastic material on an axle of a toy vehicle comprising: a hub forming an integral part of the wheel and extending a substantial distance out from one side of the wheel, said hub having a bore therethrough slightly larger in diameter than the axle so that the wheel has a smooth running fit on the axle, the wall of the hub being relatively thin and of substantially uniform cross section throughout the length thereof; an integral radially inturned relatively

thin-walled flange on the axially outer end of the hub, said hub and flange by virtue of their relatively thin walls and the fact that they are formed of plastic material being slightly resilient to permit slight expansion of the aperture defined by the flange; and a coaxial button-like extension on the outer end of the axle, the neck portion of which has a diameter substantially smaller than that of the axle and slightly smaller than the normal size of the aperture defined by the flange, and the head of said extension having a diameter slightly larger than that of the normal size of the aperture defined by said flange and being tapered at its outer end so that the flange aperture may be momentarily expanded by camming co-operation between the flange and the tapered outer end of the head, to permit the wheel to be axially pushed onto the axle with a detent-like action to a position in which the flange encircles the neck portion of said extension and axially outward displacement of the wheel off of the axle is precluded by engagement of the outer face of the flange with 20 the underside of the head.
